US0D1059727S

(12) **United States Design Patent** (10) **Patent No.:** **US D1,059,727 S**
(45) **Date of Patent:** **** Jan. 28, 2025**

(54) **BANKING TERMINAL**

(71) Applicant: **HYOSUNG TNS INC.**, Seoul (KR)

(72) Inventors: **Hee Youn Lee**, Gwangju-si (KR); **Jae Min Cha**, Seongnam-si (KR); **Jae Min Park**, Anyang-si (KR); **Dong Hee Kim**, Seoul (KR)

(73) Assignee: **HYOSUNG TNS INC.**, Seoul (KR)

(**) Term: **15 Years**

(21) Appl. No.: **29/874,985**

(22) Filed: **Apr. 27, 2023**

(30) **Foreign Application Priority Data**

Feb. 6, 2023 (KR) 30-2023-0004350

(57) **CLAIM**

The ornamental design for a banking terminal, as shown and described.

DESCRIPTION

FIG. 1 is a perspective view of a banking terminal, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines represent unclaimed subject matter and form no part of the claimed design.

1 Claim, 7 Drawing Sheets
